US00D868573S

(12) **United States Design Patent** (10) **Patent No.:** **US D868,573 S**
(45) **Date of Patent:** **** Dec. 3, 2019**

(54) **POST CLAMP**

(71) Applicant: **WeatherSure Systems, Inc.**, Denver, CO (US)

(72) Inventors: **Rodney Owens**, Denver, CO (US); **Phillip Owens**, Denver, CO (US)

(73) Assignee: **WeatherSure Systems, Inc.**, Denver, CO (US)

(**) Term: **15 Years**

(21) Appl. No.: **29/611,309**

(22) Filed: **Jul. 20, 2017**

(51) LOC (12) Cl. **08-08**

(52) U.S. Cl.

USPC **D8/394**

(57) **CLAIM**

The ornamental design for a post clamp, substantially as shown and described.

DESCRIPTION

FIG. 1 is a top perspective view of a segment of a post clamp, shown separately for ease of disclosure;

FIG. 2 is a bottom perspective view of the post clamp of FIG. 1;

FIG. 3 is a rear view of the design corresponding to FIG. 1;

FIG. 4 is a front view of the design corresponding to FIG. 1;

FIG. 5 is a right-side view of the design corresponding to FIG. 1;

FIG. 6 is a left-side view of the design corresponding to FIG. 1;

FIG. 7 is a top view of the design corresponding to FIG. 1;

FIG. 8 is a bottom view of the design corresponding to FIG. 1; and

FIG. 9 is a top perspective view of the post clamp, shown with environment;

FIG. 10 is a bottom perspective view corresponding to FIG. 9;

FIG. 11 is a front view of the design corresponding to FIG. 9;

FIG. 12 is a rear view of the design corresponding to FIG. 9;

FIG. 13 is a right-side view of the design corresponding to FIG. 9;

FIG. 14 is a left-side view of the design corresponding to FIG. 9;

FIG. 15 is a top view of the design corresponding to FIG. 9;

FIG. 16 is a bottom view of the design corresponding to FIG. 1; and,

FIG. 17 is a top perspective view of the post clamp, shown with environment and in use.

The broken lines depict environment that forms no part of the claimed design.

1 Claim, 10 Drawing Sheets
